SUCTION CUP TIMING MECHANISM
CONTROLLED ANIMATED TOY

Voorhis F. Wigal, Rocky River, Ohio

Application April 30, 1953, Serial No. 352,086

9 Claims. (Cl. 46—123)

1

This invention relates to escapement mechanisms, and in particular relates to a new and novel escapement mechanism having particular application in the field of mechanical toys.

In the past, there have been described the use of certain surface-adhering suction cups, which are "bled" in various ways to relieve the adherence of the same to the sheer surface being traversed by a climbing toy.

In one form of prior art, bleeding of the suction cups was effectuated by provision of communicating parts between the interior and exterior faces of the suction cup. In this manner, the formation of a theoretically imperforate was obviated. It has been discovered that substantially the same result can be obtained by the roughening of either the suction cup or the reaction surface to which the suction cup adheres.

It is therefore one object of this invention to utilize this "bled" type of suction cup, either perforate or imperforate in conjunction with an appropriate surface, as a timing mechanism for an escapement device.

It is a further object of this invention to utilize a vacuum cup with a leak therein, to impart intermittent animation to a simulated toy animal.

These and other objects of the invention will become more apparent upon reading of the specification, considered in the light of the accompanying drawings.

Of the drawings:

Figure 1 is a top plan view partly broken away and in section, of a toy fish having the new and novel escapement mechanism incorporated therein.

Figure 2 is a side elevation, partly broken away and in section, and showing the vacuum cup in adhered relationship to the reaction surface.

Figure 3 is a view similar to Figure 2 but showing the vacuum cup separated from the reaction surface.

Figure 4 is a side elevation, partly broken away and in section, and illustrating a modification of the invention.

Figure 5 is a view taken on the lines 5—5 of Figure 4.

Figures 6, 7 and 8 are cross-sectional elevations of various types of suction cups that may be used in the construction of the escapement mechanism.

Figure 9 represents a modified form of the invention.

In the preferred form of the invention shown in Figures 1, 2 and 3 of the drawings, the driving

2

mechanism 10, and the escapement mechanism (indicated generally by the numeral 20), that is employed to control the same, are shown mounted within the interior of a hollow toy 11, that resembles, in configuration, a simulated toy fish, having a hollow body 11a, a head portion 11b, and a tail or fin portion 11c. The arrangement of the component parts is such that while the driving and escapement mechanisms are both mounted on a plate 21 that is secured to the hollow body 11a as at 12, the hollow body 11a is provided with longitudinal slots 44, 45, to permit the end of a rotor arm 16a, to swing out therethrough. In this manner, during the operation of the toy, the end of the rotor arm 16a, will, upon rotation, extend through the slots 44, 45, and strike the external surface upon which the toy is resting, causing the same to be repelled from the surface in simulation of a fish jumping when on dry land.

Referring now to the driving mechanism 10, the same is shown as including a shaft 15, journaled between opposed supports 13, 14, and freely extending through appropriate apertures provided in the opposed walls of the hollow body 11a. Positioned about the shaft 15, adjacent the central portion thereof, may be a rotor 16, mounted in relatively rotatable relationship to the shaft 15, and including a rotor arm 16a, which is engaged by the escapement mechanism 20 so as to restrict rotation thereof in a manner to be described. To the end of providing a motivating force to cause relative rotation of the rotor 16 with respect to the shaft 15, there is provided a driving spring 17, positioned around one portion of the shaft 15 and having the respective ends 17a, 17b thereof, secured, respectively to the shaft 15, and the rotor 16. (See Figure 1.) Winding of the driving spring is facilitated by providing an externally presented winding key 18, while unintentional unwinding of the driving spring 17 is prevented by employing a ratchet wheel 19, in conjunction with a pawl member 19a.

While the preferred form of escapement mechanism 20 used to control the rotation of the rotor 16, is shown mounted between the opposed supports 13, 14, around a pin 21, the pivotal movement of the same about the pin 21 is controlled by virtue of the novel construction of the escapement mechanism 20, hereinafter to be described. To this end, the escapement mechanism 20 is shown including an arm member 22, generally known in escapements as a pallet arm having one end thereof pivoted about the pin 21, and having the opposite end thereof apertured

for reception therein of the flexible shank 23 of a suction cup 24. Integrally connected to the pivoted end of the arm 22, and extending divergently therefrom, may be extension arms or cam means 25, 26, successively engageable with the rotor arm 16 to urge respective disengagement and subsequent re-engagement of the suction cup 24 with a reaction surface 27a, provided on a plate 27. While the extension arms 25, 26 are acted upon by the rotor arms 16a to impart rotational movement upon the suction cup 24 with respect to the reaction surface 27a, release of the suction cup 24 from the reaction surface 27a will not take place until sufficient air enters the underside of the suction cup 24 to break the seal of the same with the reaction surface 27a. By like token, the end of the extension arm 25 is shown bent as at 25a, so as to more efficiently transmit the force presented by the rotor arm 16a when the same is under tension and exerting force to disengage the suction cup 24 from the reaction surface 27a.

In use or operation of the improved timing device for escapement mechanisms in conjunction with a simulated, hollow toy fish, the winding key 18 is first turned in clockwise direction (Figure 2), while the rotor arm 16a is held against rotation during the winding interval. With the driving mechanism thus wound and secured against accidental unwinding by virtue of the ratchet wheel 19 and the usual ratchet pawl 19a, the toy may be placed upon the external surface and the rotor arm 16a released, whereupon the same will rotate in a clockwise direction with the end portion passing through clearance slots 44, 45 provided in the hollow body for this purpose. Because the suction cup 24 is normally out of engagement with the reaction surface 27a, the first complete revolution of the rotor arm 16a will operate only to urge the suction cup 24 into adherence with the reaction surface 27a as a result of the moment applied to the suction cup 24 by virtue of the contact between the extension arm 26 and the tip of the rotor arm 16a. With the suction cup 24 thus adhered to the reaction surface 27a, further rotation of the rotor arm 16a will be prohibited when the same reaches the position shown in Figure 2, wherein the end of the rotor arm 16a is engaged by the bent end 25a of the extension arm 25. Because of the perforate seal formed between the suction cup 24 and the reaction surface 27a, it is manifest that the rotor arm 16a will be held in the position of Figure 2 only until sufficient air enters the underside of the suction cup 24 to break the seal that causes adherence between the suction cup 24 and the reaction surface 27a. When this seal is broken, the suction cup 24 will be urged away from the reaction surface 27a by virtue of the moment applied thereto by the extension arm 25, and pivoted to the position of Figure 3, thereby allowing the rotor arm 16a to pass the bent end 25a and subsequently to contact the extension arm 26. At this point, the motivating force of the rotor arm 16a, will cause the same to pivotally move the extension arm 26 back towards the position of Figure 2, thereby permitting the passage of the rotor arm 16a past extension arm 26, and simultaneously causing, by virtue of the moment applied, a re-engagement of the suction cup 24 with the reaction surface 27a. With the suction cup 24 thus positioned, the rotor arm 16a will rotate until striking the extension arm 25, whereupon

the releasing cycle is repeated until such time as the spring 17 is unwound.

From the foregoing it is manifest that a new and novel escapement mechanism has been presented that is capable of use in conjunction with animated toys to provide a new and novel simulated movement. It has been further shown how the timing device for the escapement mechanism is of simple, yet durable, construction, thus lending itself to economical mass production.

In Figures 4 and 5, there is illustrated a modified form of the invention, wherein simulated animation is changed from that of a fish to that of a hopping bird, by providing the driving mechanism of Figures 1-3 with a rotor 50, having a plurality of rotor arms 51, 51. As a result of this use of a multiple arm rotor 50, the rotational advancement of the same, upon release of the suction cup 24 as previously described, is considerably less than the substantially complete rotational advancement effectuated in Figures 1-3. Accordingly, the contact with the external surface is less severe and the action simulated is one of hopping rather than jumping. Complete elimination of the probability of the toy overturning can be insured by providing appropriate weights 4, 6 within the hollow body, thus permitting advance of the toy in a hopping fashion. Further modification set forth in Figures 4 and 5 include the use of a generally roughened reaction surface 50, provided on the plate 51, to prevent the formation of theoretically perfect seal when an imperforate suction cup 52 is used.

It is equally manifest that other types of rotors could be utilized in conjunction with the type of escapement mechanism set forth in Figures 1-3. For example, the rotor of Figures 1-3, could be weighted at its outer end, and made to rotate entirely within a shell or casing in simulation of a jumping bean.

Because the operation of the escapement mechanism 20 is predicated upon adherence of the suction cup 24 to the reaction surface 27a for a predetermined time interval, it is manifest that either the suction cup 24 or the reaction surface 27a should preferably be of such construction as to prevent the formation of a theoretically perfect vacuum within the concave face thereof when the same engages the reaction surface 27a. Accordingly, in Figures 4 and 5, the reaction surface 27a has been shown roughened while in Figures 6, 7 and 8, there are illustrated various types of suction cups that may be employed to the desired end. Thus in Figure 6, there is shown a suction cup 60 wherein the entrance of the air is facilitated by provision of an aperture 61, extending from the interior surface 62 to the exterior surface 63. Likewise, in Figure 7, a theoretically perfect seal is prevented by provision of a channel 70 formed on the interior surface 71 of the suction cup 72 and extending to the peripheral edge 73. In Figure 8, a generally roughened internal face portion 80, provided on the suction cup 81, insures against the formation of a theoretically perfect seal.

In Figure 9, there is shown a modification of the invention, wherein the novel releasing mechanism is illustrated incorporated in a sliding mechanism. Accordingly, the suction cup 90 is shown mounted on one end of a reciprocating yoke 91, the opposite end 92 of which is secured to conventional reciprocating means (not shown). Inclined faces 93, 94, are shown mounted on the yoke 91, the arrangement being such that a rotor arm 95, rotatable within the yoke 91, will engage

the faces 93, 94, to cause reciprocation of the yoke with respect to a reaction surface 96. In operation, the rotor arm 95, rotating in clockwise direction, first engages the inclined face 93, and urges the yoke 91 towards the reaction surface 96. When the suction cup 90 engages the reaction surface 96, the rotor arm 95 will pass the inclined face 93, and upon rotation, will engage the inclined face 94. At this point, the yoke 91 will be subjected to force tending to urge the same away from the reaction surface 96. However, movement of the yoke 91 will not be permitted until the seal between the suction cup 90 and the reaction surface 96 is broken as has been previously described. When the seal is broken, the rotor arm 95 will rotate to engage the surface 93 for repetition of the cycle.

Accordingly, other modifications of the invention may be resorted to without departing from the spirit thereof or the scope of the appended claims.

What is claimed is:

1. An animated toy comprising: a body; a power driven rotor mounted for unidirectional rotation within said body and having a radially projecting portion rigid therewith, said rotor being disposed so that the path of movement of said projecting portion projects through an opening beyond the confines of said body; escapement means adapted to coact with said rotor to permit intermittent rotational advancement thereof whereby intermittent motion is imparted to said body by contact of said projecting portion with the surface on which said body is resting; a pallet arm member in said escapement means adapted to be engaged by said projecting portion of said rotor to permit intermittent, timed rotation of said rotor; a reaction surface on said body; a suction cup carried by said pallet arm member capable of temporary adherence to said reaction surface and to therefore arrest the movement of said pallet arm member; means on said pallet arm adapted to be activated by said rotor to move said pallet arm so as to bring said suction cup in temporary adhering engagement with said reaction surface during each revolution of said rotor; and abutment means on said pallet arm adapted to be thereafter engaged by said projecting portion of said rotating member when said pallet arm and said suction cup are in such adhering engagement, whereby the motion of said rotor is arrested, said abutment means and said arm having a configuration such that when said suction cup subsequently becomes disengaged said rotor is released for further rotary movement, until said abutment means is again engaged by said projecting portion of said rotor.

2. An animated toy comprising: a body; a power driven rotor mounted for unidirectional rotation within said body and having a radially projecting portion rigid therewith, said rotor being disposed so that the path of movement of said projecting portion projects through an opening beyond the confines of said body; escapement means adapted to coact with said rotor to permit intermittent rotational advancement thereof whereby intermittent motion is imparted to said body by contact of said projecting portion with the surface on which said body is resting; a pallet arm member in said escapement means adapted to be engaged by said projecting portion of said rotor to permit intermittent, timed rotation of said rotor; a reaction surface on said support; a suction cup carried by said pallet arm member, capable of temporary ad-

herence to said reaction surface, and to therefore arrest the movement of said pallet arm member; cam means on said pallet arm adapted to be momentarily engaged by said projecting portion of said rotor during each revolution thereof so as to move said pallet arm to bring said suction cup into temporary, adhering engagement with said reaction surface; and abutment means on said pallet arm adapted to be thereafter engaged by said projecting portion of said rotor when said pallet arm and said suction cup are in such adhering engagement, whereby the motion of said rotor is arrested, said abutment means and said arm having a configuration such that when said suction cup subsequently becomes disengaged said rotor is released for further rotary movement, until said abutment means is again engaged by said projecting portion of said rotor.

3. An animated toy comprising: a hollow body; a power driven rotor mounted within and unidirectionally rotatable with respect to said body; a plurality of rigid radial projections on said rotor; the path of movement of the ends thereof extending through an opening in said body; an escapement means activated by and controlling the rotation of said rotor; said escapement means comprising a reaction surface flexed with respect to said body, a pallet arm member adapted to be successively engaged by the projecting portions of said rotor to permit intermittent, timed rotation of said rotor, and a suction cup carried by said pallet arm member adapted to be moved alternately into and out of engagement with said reaction surface by said rotor and being capable of temporary adherence thereto so as to control the movement of said pallet arm member, means on said pallet arm adapted to be activated by said rotating member to move said pallet arm so as to bring said suction cup into a plurality of temporary adhering engagements with said reaction surface during each revolution of said rotating member, and abutment means on said pallet arm adapted to be engaged by one of said projecting portions of said rotor when said pallet arm and said suction cup are in such adhering engagement, whereby the motion of said rotor is arrested, said abutment means and said arm having a configuration such that when said suction cup subsequently becomes disengaged said rotor is released for further rotary movement, until said abutment means is again engaged by one of said projecting portions of said rotor.

4. An animated toy comprising: a hollow body having an opening therein, a power driven rotor mounted within and unidirectionally rotatable with respect to said body, a plurality of rigid radial projections on said rotor, the path of movement of the ends thereof extending through an opening in said body; and escapement means activated by and controlling the rotation of said rotor; said escapement means comprising a reaction surface fixed with respect to said body, a pallet arm member adapted to be successively engaged by the projecting portions of said rotor and to permit intermittent, timed rotation of said rotor, a suction cup carried by said pallet arm member adapted to be moved alternately into and out of engagement with said reaction surface by said rotor and being capable of temporary adherence thereto so as to control the movement of said pallet arm member, cam means on said pallet arm adapted to be momentarily engaged by each of said radial projections on said rotor during each revolution thereof so as to move said

pallet arm to bring said suction cup into temporary, adhering engagement with said reaction surface, and abutment means on said pallet arm adapted to be thereafter engaged by one of said projections when said pallet arm and said suction cup are in such adhering engagement, whereby the motion of said rotor is arrested, said abutment means and said arm having a configuration such that when said suction cup subsequently becomes disengaged said rotor is released for further rotary movement, until said abutment means is again engaged by one of said radial projections on said rotor.

5. An animated toy comprising: a body; a unidirectional, power driven, rotating member mounted in said body and having a radially projecting portion rigid therewith, said member being disposed so that the path of movement of the end of said member projects through an opening in said body beyond the confines of that portion of said body normally in contact with the supporting surface on which said toy is disposed; power means for continuously urging said rotating member to rotate and to strike said supporting surface; a bearing member on said body; an arm movable on said bearing member; a reaction surface on said body; a suction cup carried by said arm capable of temporary adherence to said reaction surface, a cam surface on said arm adapted to be momentarily engaged by said projecting portion of said rotating member to move said arm on said bearing member in a direction such as to cause said suction cup to be brought into temporary adhering engagement with said reaction surface; and a second cam surface on said arm adapted to be subsequently engaged by said projecting portion of said rotating member within a single revolution thereof when said suction cup is disposed in adhering engagement with said reaction surface, and while so engaged to continuously urge said suction cup out of engagement with said reaction surface, said second cam surface and said arm having a configuration such that when said suction cup subsequently becomes disengaged said rotating member is released or further rotary movement, until said second cam surface is again engaged by said projecting portion of said rotating member.

6. An escapement mechanism comprising: a support; a unidirectional power driven rotating member having a radially projecting portion mounted on said support; a bearing on said support; a pallet arm movable about said bearing disposed in cooperative association with said projecting portion of said rotating member, a suction cup secured to said pallet arm at a point in spaced relation to said bearing; a reaction surface disposed in cooperative association with said suction cup; means on said pallet arm adapted to be activated by said rotating member to move said pallet arm so as to bring said suction cup into temporary adhering engagement with said reaction surface during each revolution of said rotating member; and abutment means on said pallet arm adapted to be thereafter engaged by said projecting portion of said rotating member when said pallet arm and said suction cup are in such adhering engagement, whereby the motion of said rotating member is arrested, said abutment means and said arm having a configuration such that when said suction cup subsequently becomes disengaged said rotating member is released for further rotary movement, until said abutment means is again engaged by said projecting portion of said rotating member.

7. An escapement mechanism comprising: a support; a unidirectional power driven rotating member having a radially projecting portion mounted on said support; a bearing on said support; a pallet arm movable about said bearing disposed in cooperative association with said projecting portion of said rotating member, a suction cup secured to said pallet arm at a point in spaced relation to said bearing; a reaction surface disposed in cooperative association with said suction cup; cam means on said pallet arm adapted to be momentarily engaged by said projecting portion of said rotating member during each revolution thereof so as to move said pallet arm to bring said suction cup into temporary, adhering engagement with said reaction surface; abutment means on said pallet arm adapted to be thereafter engaged by said projecting portion of said rotating member when said pallet arm and said suction cup are in such adhering engagement whereby the motion of said rotating member is arrested, said abutment means and said arm having a configuration such that when said suction cup subsequently becomes disengaged said rotating member is released for further rotary movement, until said abutment means is again engaged by said projecting portion of said rotating member.

8. An escapement mechanism comprising: a support; a bearing on said support; a pallet arm movable about said bearing; a reaction surface provided on said support adjacent said arm; a suction cup secured to said arm at a point remote from said bearing, and being capable of temporary adherence with said surface; a unidirectional, power driven, rotating member mounted on said support in association with said arm and having a radially projecting portion; cam means on said arm adapted to be engaged by said projecting portion of said rotating member to move said arm on said bearing so that said suction cup is brought into temporary adhering engagement with said surface; and additional cam means on said arm adapted to be thereafter engaged by said projecting portion of said rotating member within a single revolution thereof whereby the motion of said rotating member is arrested and said arm may be urged to move said bearing in a direction such as to cause disengagement of said suction cup with said surface, said additional cam means and said arm having a configuration such that when said suction cup subsequently becomes disengaged said rotating member is released for further rotary movement, until said additional cam means is again engaged by said projecting portion of said rotating member.

9. An escapement mechanism comprising: a support; a bearing on said support; a pallet arm movable about said bearing; a reaction surface provided on said support adjacent said arm; a suction cup secured to said arm at a point remote from said bearing and being capable of temporary adherence with said surface; a unidirectional, power driven, rotating member mounted on said support in association with said arm and having a radially projecting portion; an abutment surface on said arm adapted to be momentarily engaged by said projecting portion of said rotating member to move said arm on said bearing member in a direction such as to cause said suction cup to be brought into temporary adhering engagement with said reaction surface; and a second abutment surface on said arm adapted to be subsequently engaged by said projecting portion

of said rotating member and to arrest the motion thereof during the time said suction cup is so disposed in temporary adhering engagement with said reaction surface, said second abutment surface and said arm having a configuration such that when said suction cup subsequently becomes disengaged said rotating member is released for further rotary movement, until said second abutment surface is again engaged by said projecting portion of said rotating member.
